LIPSTICK CASE

Iver Rich, New York, N. Y.

Application October 5, 1944, Serial No. 557,236

5 Claims. (Cl. 206—56)

1

This invention relates to improvements in holders or containers for lipsticks, and more particularly to a new and improved type of retractable lipstick case. The invention however is not to be limited to lipsticks as the improved device can be used to hold any cosmetic or the like in stick form, such as shaving soap, lip pomade, etc.

The invention has among its objects the provision of an improved retractable lipstick case of novel construction, configuration and appearance, and which is easy to manipulate by one hand alone.

Another object of the invention is to provide a retractable lipstick case of the push type comprising a minimum number of parts and which is reliable and efficient in its operation.

Another object of the invention is to provide a retractable lipstick case of the push type wherein the cover and body member of the case are provided with cooperating engaging means, thus preventing accidental displacement of the cover from the case.

Still another object of the invention is to provide a retractable lipstick case of the push type wherein the bottom wall of the body of the case is removable, thus permitting the convenient insertion of a refill after the original has been consumed.

Other objects of the invention will be apparent from and set forth in the following description and drawing which illustrates a preferred embodiment thereof.

Fig. 1 is a front elevation of a lipstick case embodying the present invention, the cover of the case being shown partially broken away.

Fig. 2 is a central longitudinal sectional view taken on the line 2—2 of Fig. 1.

Fig. 3 is a transverse sectional view taken on the line 3—3 of Fig. 2.

Fig. 4 is a transverse sectional view along the line 4—4 of Fig. 2.

Fig. 5 is a bottom plan view of the device.

Fig. 6 is a longitudinal sectional view of the case with the cover removed therefrom, showing the lipstick in its projected position and the carrier extended to the limit of its forward or upward movement.

Referring to the drawing, the improved device comprises the tubular casing 10 and the cover 11, both said members being substantially square in cross-section, as shown in Figs. 3 and 4. It will be noted however that the inside of casing 10 is cylindrical. Said casing 10 and cover 11 are preferably molded from any suitable plastic or resin such as, for example, cellulose acetate

and the like, or from any suitable thermal setting plastic molding material.

Casing 10 is open at each of its respective opposite ends, its inner end being closed by base member 12, and its outer end by cover 11. Said casing 10 is formed with the inward lateral shoulder 13 at a point slightly above the middle thereof. For convenience, I have designated that portion of casing 10 above shoulder 13 by the reference numeral 14. Said portion 14 of casing 10 is offset with respect to the lower portion of casing 10.

Slidably positioned within casing 10 and freely movable longitudinally therein is the cylindrical carrier or lipstick holder 15. A tongue 16 is formed in the cylindrical side wall of said carrier, said tongue being partially severed from said wall and deflected or bent at right angles therefrom. Said tongue 16 serves as a base or support on which the lipstick L rests, the bottom face of said lipstick L abutting the top face of tongue 16, as shown in Figs. 2 and 6. The lower portion of lipstick L is frictionally held by the cup-like portion of carrier 15, located above tongue 16. For convenience, I have designated said portion of carrier 15 by the reference numeral 17. Carrier 15 may be made from any suitable metal or the like, preferably brass.

Secured to carrier 15 adjacent the lower end thereof is the coupling-pin 18. The shank of said pin 18 passes through a longitudinal slot 19 formed in front wall 20 of casing 10 and the head of said pin 18 is secured to the longitudinal finger piece 21. The said slot 19 is located within a longitudinal groove 26 formed in front wall 20, said groove extending from the bottom of said front wall to the top thereof. Finger piece 21 is slideable within said groove or recess 26. The said finger piece 21 is transversely ribbed so that the finger of the user will not slip therefrom. It will be noted that longitudinal slot 19 extends from the base of casing 10 to a point slightly below shoulder 13 of said casing 10.

It is accordingly apparent that movement of finger piece 21 will cause carrier 15 to move therewith. By pushing the said finger piece 21 forwardly carrier 15 is caused to advance longitudinally, thus partially projecting lipstick L out of casing 10. Fig. 6 shows carrier 15 extended to the limit of its forward or upward movement. In this position, coupling pin 18 is located at the upper end of longitudinal slot 19, the upper end of said slot 19 serving as a stop to limit the forward or upward movement of carrier 15. Fig. 2 shows the carrier 15 retracted to the limit

of its inward or downward movement. This is accomplished merely by moving a pushing finger piece 21 inwardly or downwardly to the full extent of its inward movement. In this position, the bottom end of said carrier 15 abuts the top face of bottom member 12.

It will be noted that although there is sufficient frictional engagement between carrier 15 and the inside of casing 10, the said carrier 15 is movable longitudinally in said casing 10 and may be advanced or retracted at any point within the confines of the upper and lower stop limits.

As regards bottom piece or member 12, this is removably secured to the bottom of casing 10 in any desired manner. In order to close the bottom end of longitudinal slot 19 in front wall 20, bottom piece 12 is formed with the integral upstanding flange or lip 22, the inner face of said flange or lip 22 abutting the lower end of front wall 20. Member 12 and its integral flange 22 act as a stop to limit the inward or downward movement of finger piece 21.

In order to replace a used up lipstick carrier 15 is brought to the lowermost position shown in Figs. 1 and 2. Bottom piece 12 is then removed and the entire carrier 15 and finger piece 21 and coupling pin 18, as a unitary article, is withdrawn from casing 10 through the opening in the bottom wall thereof. The old lipstick is then removed from the upper portion 17 of carrier 15 and replaced by a refill. Carrier 15 is then inserted in casing 10 through the opening in the bottom wall thereof and said opening is then closed by bottom piece 12.

Upper portion 14 of casing 10 is provided in the front wall 25 thereof with a longitudinal undercut groove or recess 23, said groove 23 extending from shoulder 13 to a point slightly below the upper end of portion 14. Groove 23 is aligned with longitudinal groove 26 and longitudinal slot 19 in front wall 20 and the width of said groove 23 is substantially equal to or slightly larger than the width of finger piece 21. Said groove 23 is in effect an extension of groove 26. Groove 23 has a dual function. First, it is adapted to receive finger piece 21 when said finger piece 21 is pushed or moved forwardly or upwardly. Fig. 6 shows finger piece 21 riding within said groove 23. Secondly, groove 23 is adapted to receive longitudinal projection or boss 24 formed on the inner face of the front wall of cover 11. In this manner cover 11 is securely held to casing 10, the said construction preventing the accidental dislodging or displacement of the cover 11 from the case 10. Fig. 4 clearly shows the interlocking of projection 24 with groove 23.

It will be noted from Figs. 3 and 4 that finger-piece 21 and projection 24 are dove-tailed in cross-section. Such configuration permits the ready reception of said members by undercut groove 23.

I have illustrated and described a preferred embodiment of my invention, but it is obvious that numerous changes, omissions and alterations may be made without departing from its spirit. It is not imperative that the case be square in cross-section. It may, if desired, be of polygonal or other cross-section. Likewise, the casing may be made of metal or any other suitable material.

It should be noted that whenever the finger-piece 21 is pushed or moved forwardly or upwardly no part of the lipstick L is visible through longitudinal slot 19. This is so because the lip-

stick L rests upon tongue 16 of carrier 15 and does not extend to the base of said carrier. This is far advantageous over the usual push type of lipstick casing for the reason that in the usual cases of this type, the lipstick is visible through the longitudinal slot and there is usually a certain amount of seepage therethrough. With the instant device, only the desired amount of lipstick to be used is exposed by the user. 10 There is no chance of any dust or foreign matter contacting the lipstick through slot 19.

I claim:

1. A lipstick case of the character described comprising, in combination, a tubular casing member having an inward lateral shoulder formed in the outer face thereof, said shoulder dividing said casing member into an upper section and a lower section, said upper section being offset with respect to said lower section and having a longitudinal recess formed therein, a longitudinal recess in the lower section extending throughout the length thereof and forming a continuation of the recess in the upper section, a carrier member positioned within said casing and longitudinally movable therein, an elongated finger-piece member located externally to said casing member and being connected to said carrier member through a longitudinal slot formed in the longitudinal recess of the lower section of said casing, said finger-piece member having a length substantially equal to the length of the lower section and being longitudinally movable in unison with said carrier member, a tongue formed in the side wall of said carrier, said tongue being partially severed from said wall and deflected at an angle therefrom, the portion of the carrier member located above said tongue being adapted to receive and hold a lipstick.

2. A lipstick case of the character described comprising, in combination, a tubular casing member formed of a molded composition, having an inward lateral shoulder formed in the outer face thereof, said shoulder dividing said casing member into an upper section and a lower section, said upper section being offset with respect to said lower section and having a longitudinal recess formed therein, a longitudinal recess in the lower section extending throughout the length thereof and forming a continuation of the recess in the upper section, a cylindrical carrier member positioned within said casing and longitudinally movable therein, an elongated finger-piece member longitudinally movable in said recess and having a length substantially equal to the length of the lower section, said finger-piece member being connected to the lower end of said carrier member through a longitudinal slot formed in the longitudinal recess of the lower section of said casing, said carrier being advanceable and retractable in unison with said finger-piece member, a tongue formed in the cylindrical side wall of said carrier, said tongue being partially severed from said wall and bent at right angles therefrom, the portion of the carrier member located above said tongue being adapted to receive and hold a lipstick.

3. A lipstick case of the character described comprising, in combination, a tubular casing member formed of molded composition and having an inward lateral shoulder formed in the outer face thereof, said shoulder dividing the said casing into an upper section and a lower section, said upper section being offset with respect to said lower section and having a longitudinal recess formed therein, a removable cover

member for said casing member, said cover member having a longitudinal projection on the inner face thereof, the longitudinal recess of the upper section of said casing being adapted to receive said projection and thereby lock the cover member on said casing member, a cylindrical member positioned within said casing and longitudinally movable therein, a finger-piece member longitudinally movable in a longitudinal recess formed in the lower section of said casing, said finger-piece member being connected to the lower end of said carrier member through a longitudinal slot formed in the longitudinal recess of the lower section of said casing, said carrier being advanceable and retractable in unison with said finger-piece member, a tongue formed in the cylindrical side wall of said carrier, said tongue being partially severed from said wall and bent at right angles therefrom, the portion of the carrier member located above said tongue being adapted to receive and hold a lipstick.

4. A device as claimed in claim 3, wherein the longitudinal recess of the upper section of the

casing is continuous with the longitudinal recess in the lower section, the longitudinal recess of the upper section being adapted to receive the finger-piece member when the latter is moved forwardly.

5. A device as claimed in claim 3, wherein the casing member has a removable base member positioned on the bottom thereof.

IVOR RICH.
